UNITED STATES PATENT OFFICE

155,863

DESIGN FOR A SPOON OR SIMILAR ARTICLE

Grosvenor N. Allen, Oneida, and Mary Parker Fleming, Fulton, N. Y., assignors to Oneida Ltd., Oneida, N. Y., a corporation of New York

Application April 8, 1948, Serial No. 145,598

Term of patent 14 years

(Cl. D54—12)

To all whom it may concern:

Be it known that we, Grosvenor N. Allen and Mary Parker Fleming, citizens of the United States, residing at Oneida, county of Madison, and State of New York, and at Fulton, county of Oswego, and State of New York, respectively, have invented a new, original, and ornamental Design for a Spoon or Similar Article, of which the following is a specification, reference being had to the accompanying drawing, forming a part thereof, in which:

Figure 1 is a front view of a spoon, showing our new design;

Figure 2 is a back view of the spoon; and

Figures 3, 4 and 5 are sections taken on the respective lines 3—3; 4—4 and 5—5 of Figure 1.

The essential features of our design for a spoon or a similar article reside in the configuration

of the handle in combination with the particular type of ornamentation and the manner in which it is applied thereto.

We claim:

The ornamental design for a spoon or similar article, substantially as shown and described.

GROSVENOR N. ALLEN.
MARY PARKER FLEMING.
